UNITED STATES PATENT OFFICE

2,390,630

HEATING MEANS

Harry Stewart Wheller, Elizabeth, N. J., assignor
to L. J. Wing Mfg. Co., New York, N. Y., a corporation of New York

Application April 6, 1943, Serial No. 481,967

17 Claims. (Cl. 98—40)

The present invention relates to heating devices conventionally termed "unit heaters," and more particularly to that type in which air is forced by a fan through a heater and the thus heated air then discharged through outlets into a room or space in which the heating device is located and into the working area to which the heated air is discharged, such as the heaters described and claimed in Patent No. 2,000,112 granted to me May 7, 1935.

The heaters, which are the subject of that patent and to which the invention of this application is an improvement, are provided with a revolving air discharge casing, preferably having a plurality of outlets through which the heated air is discharged to the working area.

In order to direct the stream of air discharged from each outlet continuously in succession to all points of the room or working area in which the heater is located, the discharge casing is mounted on the heater so that it may be rotated thereabout to accomplish such operation by which the heated air is continuously successively discharged to all parts of the room or working area about the heater and thereby uniformly diffused throughout the entire working area.

Since the air is thus discharged in equal quantity to each part of the room or working area about the circumference of the revolving heater discharge, rotatable discharge unit heaters of the former construction, as described in my said patent, theoretically operate most efficiently in a symmetrical area such as a square area, as distinguished from a non-symmetrical area, such as an oblong area.

Where, however, such heaters operate in a working area which is not uniform in arrangement about the axis of revolution of the discharge casing, for example, such as an oblong room or area, all parts of the room or area will not be uniformly heated. For example, if the heater is in the center of an oblong room, the same quantity of air is sent to the smaller areas at the sides of the room as is sent to the larger areas at the ends of the room. Therefore, the smaller areas at the sides will be heated to a greater extent than the larger areas at the ends, and thus all parts of the room will not be uniformly heated.

My present invention, therefore, contemplates

the provision of a unit heater, having a revolving discharge, so constructed and arranged that it will operate as efficiently in a non-uniform area such as an oblong space, as it will in a uniform or square area.

My invention, therefore, in a revolving discharge unit heater, provides means, such as a deflector or damper, whereby the heated air is not discharged but is obstructed or blocked off in a selected direction which requires less heat through an outlet which becomes closed in that direction as it is revolved about the heater, such as the narrow part of the oblong room or space. By providing such means, the revolving discharge spontaneously or automatically does not supply heated air to those portions of the space or room wherein it is not required in full amount.

My invention still further contemplates the provision of a damper or deflector means, the position which at the periphery of revolution of the discharge casing of such a unit heater may be selectively changed to any desired position about the axis of heater revolution relative to the working area in which the heater is located so that air will not be discharged in the selected direction through an outlet as it is brought into registration or alignment with the damper or deflector means whereat it has been positioned. Such provision permits the universal application of unit heaters of a general design to working areas or rooms having any type of space configuration or heat requirement, without requiring that a given unit heater be designed for the particular shape of the space, room or working area in which it is to be located.

My invention yet further contemplates the provision of a damper or deflector means, the size or area of which, in addition to its relative position in the heater, may be selectively changed so that the amount of heated air discharged to any particular part of the working area or room may also be increased or decreased, as desired.

These, other and further objects, features and advantages of the present invention will be clear from the following description and the drawings relating thereto in which

Fig. 1 is an elevational view of a heater according to my invention.

Fig. 2 is a bottom plan view thereof, the bottom

wall broken away to show the damper means associated therewith.

Fig. 3 is a section of the discharge casing on the line 3-3 of the Fig. 2 and showing the heater but omitting the motor and the fan.

Fig. 4 is a plan view of a damper means used in the practice of my invention.

Figs. 5 and 6 are respectively side and front elevations thereof, the latter view partially broken away to show the extension slides or plates.

Fig. 7 is a schematic detail showing a rotatable discharge casing bearing and a damper or deflector means support.

Fig. 8 is a schematic plan view of my heater arranged in an oblong space or working area.

Since my invention is applied to unit heaters that are provided with a revolving discharge casing, examples of which have been described and claimed in Patent No. 2,000,112, granted to me, details of construction of the casing, the manner in which it is mounted and the means for revolving it need not here be given, reference being had to my said patent. In the within application, such details, in the main, will be schematically given in only sufficient detail for an understanding of the present invention.

In that practical embodiment of my invention, as I have practiced it, and which I have illustrated in the drawings by way of example, referring now to Figs. 1 to 3, the heater casing 10 is preferably suspended overhead, as to the ceiling of a room in the selected position therein, in any suitable manner known in the art and which, therefore, need not be described. It will, of course, be understood that my invention may be applied to any type of heater having a revolving discharge, as for example, a wall or floor type, and that I do not intend to limit myself to the specific structure here illustrated.

The heater casing 10 is provided with conventional finned heating tubes, connected to the steam heating system (neither here illustrated as they are well known) and the air to be heated is directed through the casing 10 over the heating tubes by the fan 12, and discharged from the rotatable discharge casing 14 through the outlets 16 thereon.

The motor 18 drives the fan 12 mounted coaxially therewith and may be carried on the heater casing 10, as by the arms 20, secured thereto in any suitable manner.

It will, of course, be understood that fresh, outside air may be supplied to the heater casing 10 through a duct connected thereto or already heated air may be supplied directly to a revolving discharge through a duct on which the discharge is mounted for rotation in the space to be heated.

While I have shown the discharge casing 14 with four discharge outlets 16, circumferentially arranged on the casing 90° apart, one outlet in each quadrant, it will be understood that one, two or any desired or convenient other number of outlets may be provided instead. Further, such outlets may take any other form and may be inclined at any desired angle.

The discharge casing 14 is mounted on the heater casing 10 for continuous rotation thereon, as will be explained, and so that the outlets 16 communicate with interior of the casing 10 in order that the heated air is discharged from the outlets to the space or working area in which the heater is located toward that part thereof to which the outlet in its motion is directed.

In order to deflect the heated air, as it issues

therefrom, each outlet 16 preferably has provided the louvers or baffles 22, which are pivotally secured at the sides 24 of the outlet as by means of the bolts 26, which bolts are arranged to permit adjustment of the louvers or baffles to any selected angle.

As pointed out in my said Patent No. 2,000,112, in order to eliminate certain disadvantages in unit heaters in which the outlets are stationary, such as, the production of adjacent and alternate columns or strata of heated and cooler air throughout the space or working area in which the heater is located, the discharge casing is mounted in the heater for rotation thereon and different means for driving it are provided.

The heated air discharge outlets are successively moved and directed continuously through and toward contiguous parts of the working area, to direct streams of heated air at intervals to each and every given point in the working area so that certain sections only of the working area continuously receive a blast of heated air, as is the case with the heaters having stationary discharge casings.

With the heater here serving as an illustration of the present invention, as practiced by me in one form thereof, the discharge casing 14 is driven by a separate motor 28, carried on the platform or apron 30, of a supporting bracket on the heater casing by means of the pulley 32 coaxially mounted on the motor 28 shaft and the belt 34 which rides in the groove 35 in the upper annular wall 36 of the discharge casing.

It is unnecessary to illustrate the junction or bearing between the annular wall 36 of the rotating discharge 14 and a corresponding flange or collar (not shown) depending from the heater casing 10 or a means for taking up any lateral play or displacement of the revolving casing, as these are illustrated in my said Patent No. 2,000,112 or illustrate a further construction to provide an air seal between the heater casing and the revolving discharge casing described and claimed in Patent No. 2,252,954 granted to me and to which reference is also made for application here.

In the illustration shown in the appended drawings, a bearing 38 (schematically illustrated since forms thereof are well known) for the revolving discharge 14 may be carried as on the shaft 40 secured to stationary supporting arms 42 on the heater casing 10. The rotating outer housing or race 44 of the bearing 38, which is preferably a ball or roller bearing, is secured for rotation to the carrying arms 46 on the rotatable discharge casing 14.

It will be recognized that the same quantity of air will be discharged from each outlet 16, as it revolves about its axis of rotation, successively to the contiguous parts of the working area or room in which the heater is placed. A revolving discharge, therefore, operates theoretically most efficiently in a symmetrical area, such as a square area, at the center of which it may be located, since each surrounding part (because the working area is uniformly disposed about the heater) must equally receive the stream of heated air issuing from a rotating discharge outlet.

But, on the contrary, when a heater of this kind operates in an area that is not uniform about the point of heater suspension, as for example, in the oblong area or room schematically illustrated in Fig. 8, the parts thereof adjacent the side walls 48 and 50 will be relatively over-heated since each outlet discharges thereat the

same quantity of heated air as it discharges to the larger parts of the working area adjacent to the end walls 52 and 54.

The present invention, therefore, provides a deflector or damper means which may be fixed in selected position about the axis of rotation 56 of the casing 14 at the periphery thereof so that each outlet 16 is automatically or spontaneously closed (or partially) as it is brought into registration or alignment with a deflector or damper means to shut off or decrease delivery of heated air to that part of the area or space where it is to be limited.

Where a four way type of discharge casing is used, I have used a pair of opposed dampers 58 and 60, circumferentially arranged at the periphery of rotation of the discharge casing and 180° apart. The dampers 58 and 60 are removably secured to the rod 62, which enters the eye 64 in the supporting arm 66 and the eye 68 in the upper supporting arm 10 by means of the locking bolts or set screws 70 and 72, which engage the flats 71 and 73 on the rod 62.

The damper carrying rod 62 is carried centrally of the discharge casing on the shaft 40 to which it is secured by the pin 67 and lock nut 69, inside the housing or race 76 of the bearing 38 and which inner housing or race 76 may be threaded to the shaft 40.

To secure a damper to its supporting arm, I preferably spotweld one element 75 of a clip to the damper and secure the other element 77 of the clip to the supporting arm, as by the bolts 79.

It will be recognized that either one or both of the dampers may be removed or one, two or more dampers used and their position about the axis of rotation 56 selectively changed or adjusted to thereby provide a heater, as here contemplated, that is universally adaptable to a room of any shape or configuration.

Referring now to Fig. 8, upon the discharge casing assuming during its rotation the position there illustrated, the maximum quantity of heated air is delivered from the uncovered or unobstructed outlets A and B and no heated air or a minimum quantity thereof delivered from the outlets C and D closed or obstructed by the dampers 58 and 60.

As the casing 16 is rotated in the direction of the arrows 78, the outlets C and D are gradually uncovered and unobstructed so that a gradually increasing amount of heated air (between the minimum and maximum) is delivered by them.

Conversely as the outlets A and B approach and are brought into registration or alignment with the dampers 58 and 60 they are gradually covered and obstructed so that a gradually decreasing amount of heated air (from maximum to minimum) is delivered by them.

Thus, a long narrow room or non-uniform space is given the advantages of revolving heat distribution without sacrifice in efficiency, by obstructing or cutting off the delivery of air in that direction where it is not required or should be limited in amount.

Where the shape or configuration of the space or room or other conditions make it desirable, I provide a damper, the size or area of which may be increased to cut off or obstruct the delivery of heated air through a larger section about the axis of rotation in the selected direction.

To accomplish this, referring now to Figs. 4, 5 and 6, the edges of a damper may be bent over to form the upper 80 and lower 82 depending lips,

which form rail-like grooves, in which the damper extension slides or plates 84 and 86 ride.

By moving the extension plates together so that their inside edges 88 and 90 abut, the minimum damper size is obtained and by fully separating the plates so that these edges are positioned near the outer edges 92 and 94 of the damper, the maximum damper size is obtained. Therefore, suitably positioning the plates in the damper groove, as indicated by the dotted lines in Figs. 4 and 6, the size of the damper may be selectively adjusted between the minimum and maximum to cut off delivery of heated air to any desired size of space.

It will now be apparent that I have provided a revolving discharge unit heater which may with improved efficiency be operated in a space which is not uniform in shape or configuration or a working area, parts of which have heat requirements differing from other parts and as efficiently as it would operate in a space that is symmetrical in area or a work area, the parts of which have the same heat requirement.

It will be further apparent that I have provided such a heater in which means are provided by which the air delivered in any selected direction may be automatically and spontaneously obstructed or cut off in selectively adjustable amounts to accommodate or adapt the heater to spaces of different shapes, configurations and heat requirements.

As, obviously, many variations may be made in the embodiment of my invention which I have described, within the scope and spirit of the invention, I do not intend to be limited to the exact details disclosed but intend to claim my invention as broadly as the scope of the appended claims and the state of the prior art allow.

I claim:

1. In a device for circulating a stream of air into a space in which the device is positioned, a support, a casing on the support for rotation thereabout means for rotating the casing, an outlet on the casing for continuously directing a stream of air in succession to all points of the space upon rotation of the casing about the support, a fan for circulating a stream of air through the casing and discharging it from the outlet, said outlet of selected dimensions, and a damper mounted on the support in fixed position to the axis of rotation of the casing and at the periphery thereof, said damper of selected dimensions to obstruct the outlet and shut off discharge of air therethrough upon bringing the outlet into registration with the damper during rotation of the casing about the support.

2. The device of claim 1, the damper having means for selectively fixing the position thereof on the support relative to the axis of rotation of the casing.

3. The device of claim 1, the size of the damper means being adjustable with respect to the size of the outlet.

4. A unit heater, comprising a heater section, a frame extending therefrom, a discharge casing having an outlet of selected dimensions and rotatable on the frame thereabout, means for rotating the discharge casing, a fan carried by the heater section for circulating a stream of air through the heater section and the outlet and a damper on the frame in fixed position to the axis of rotation of the casing, said damper of selected dimensions to obstruct the outlet upon bringing the outlet into registration with the

damper during rotation of the casing about the frame.

5. The device defined in claim 4, the said damper having means for selectively fixing the position thereof on the frame relative to the casing.

6. The device defined in claim 4, the size of said damper means being adjustable with respect to the size of the outlet.

7. In a heating means for circulating a stream of air in a working area in which the heating means is positioned, means for generating and heating a stream of air, a supporting means extending from the heating means, a discharge casing arranged for rotation about the supporting means, means for rotating the discharge casing, said discharge casing having an outlet, and a damper means located within the discharge casing and arranged therein to obstruct the flow of air through the outlet at certain positions upon rotation of the casing, said outlet of selected dimension and said damper means of selected dimension.

8. In a heating means for circulating a stream of air in a working area in which the heating means is positioned, means for generating and heating a stream of air, a supporting means extending from the heating means, a discharge casing arranged for rotation about the supporting means, means for rotating the discharge casing, said discharge casing having an outlet, and a damper means located within the discharge casing and arranged therein to obstruct the flow of air through the outlet at certain positions upon rotation of the casing, said outlet of selected dimension and said damper means of selected dimension, the damper having means for selective positioning thereof relative to the discharge casing.

9. In a heating means for circulating a stream of air in a working area in which the heating means is positioned, means for generating and heating a stream of air, a supporting means extending from the heating means, a discharge casing arranged for rotation about the supporting means, means for rotating the discharge casing, said discharge casing having an outlet, and a damper means located within the discharge casing and arranged therein to obstruct the flow of air through the outlet at certain positions upon rotation of the casing, said outlet of selected dimension and said damper means of selected dimension, the size of said damper means being adjustable.

10. In a unit heater for positioning in a space, means for generating and heating a stream of air, a discharge casing arranged for rotation and having an outlet of selected size for discharging the stream of air therefrom successively to contiguous parts of the space upon rotation of the casing, means for rotating the discharge casing and damper means of selected size located within the discharge casing and so arranged therein to obstruct the flow of air through the outlet upon rotation of the casing when the outlet is brought into registration with the damper means.

11. In a unit heater for positioning in a space, means for generating and heating a stream of air, a discharge casing arranged for rotation and having an outlet of selected size for discharging the stream of air therefrom successively to contiguous parts of the space upon rotation of the casing, means for rotating the discharge casing and damper means of selected size located within the discharge casing and so arranged therein to

obstruct the flow of air through the outlet upon rotation of the casing when the outlet is brought into registration with the damper means, the damper having means for selective positioning thereof relative to the casing.

12. In a unit heater for positioning in a space, means for generating and heating a stream of air, a discharge casing arranged for rotation and having an outlet of selected size for discharging the stream of air therefrom successively to contiguous parts of the space upon rotation of the casing, means for rotating the discharge casing and damper means of selected size located within the discharge casing and so arranged therein to obstruct the flow of air through the outlet upon rotation of the casing when the outlet is brought into registration with the damper means, the size of the damper means being adjustable.

13. In a unit heater for positioning in a space, means for generating and heating a stream of air, a supporting frame, a discharge casing arranged thereon for rotation thereabout, means for rotating the discharge casing, a plurality of outlets on the said casing for successively discharging from each a stream of air to contiguous parts of the space upon rotation of the casing and a plurality of spaced damper means on the frame and located within the discharge casing and so arranged as to obstruct the flow of air discharged through an outlet upon rotation of the said casing to bring an outlet into registration with a damper means.

14. In a unit heater for positioning in a space, means for generating and heating a stream of air, a supporting frame, a discharge casing arranged thereon for rotation thereabout, means for rotating the discharge casing, a plurality of outlets on the said casing for successively discharging from each a stream of air to contiguous parts of the space upon rotation of the casing and a plurality of spaced damper means on the frame and located within the discharge casing and so arranged as to obstruct the flow of air discharged through an outlet upon rotation of the said casing to bring an outlet into registration with a damper means, the position of each damper means relative to the casing being adjustable on the frame.

15. In a unit heater for positioning in a space, means for generating and heating a stream of air, a supporting frame, a discharge casing arranged thereon for rotation thereabout, means for rotating the discharge casing, a plurality of outlets on the said casing for successively discharging from each a stream of air to contiguous parts of the space upon rotation of the casing and a plurality of spaced damper means on the frame and located within the discharge casing and so arranged as to obstruct the flow of air discharged through an outlet upon rotation of the said casing to bring an outlet into registration with a damper means, the size of each damper means being adjustable.

16. In a unit heater for positioning in a space, means for generating and heating a stream of air, supporting means extending therefrom, a rotatable discharge casing on said supporting means, said casing having in each quadrant thereof an outlet for successively discharging from each outlet a stream of air to contiguous parts of the space upon rotation of the casing, said outlets uniformly spaced from each other, means for rotating the discharge casing and spaced damper means on the supporting means and located within the discharge casing and so

arranged to obstruct the flow of air discharged through an outlet upon rotation of the casing to bring the outlet into registration with a damper means.

17. In a unit heater for positioning in a space, means for generating and heating a stream of air, supporting means extending therefrom, a rotatable discharge casing on said supporting means, said casing having in each quadrant thereof an outlet for successively discharging from each outlet a stream of air to contiguous

parts of the space upon rotation of the casing, said outlets uniformly spaced from each other, means for rotating the discharge casing and spaced damper means on the supporting means and located within the discharge casing and so arranged to obstruct the flow of air discharged through an outlet upon rotation of the casing to bring the outlet into registration with a damper means, the position of a damper means relative to the casing being adjustable.

HARRY S. WHEELER.
